UNITED STATES PATENT OFFICE.

HOMER S. DOUGLASS, OF LATHROP, MISSOURI, ASSIGNOR TO MARY B. DOUGLASS, OF LATHROP, MISSOURI.

VALVE-GRINDING MECHANISM.

1,309,603.

Specification of Letters Patent.

Patented July 8, 1919.

Application filed December 23, 1918. Serial No. 267,901.

To all whom it may concern:

Be it known that I, HOMER S. DOUGLASS, a citizen of the United States, residing at Lathrop, in the county of Clinton and State 5 of Missouri, have invented a certain new and useful Improvement in Valve-Grinding Mechanisms, of which the following is a specification.

My invention relates to improvements in 10 valve grinding mechanisms.

The object of my invention is to provide a novel valve grinding mechanism which is simple in construction, cheap to manufacture, which is strong and durable and not 15 liable to get out of order, which is efficient in operation, and with which several valves may be simultaneously ground.

My invention provides further novel 20 means by which the speed of oscillation of the valve supporting members may be changed without changing the speed of rotation of the driving shaft which actuates the valve supporting members.

My invention provides still further novel 25 means for effecting oscillation of the valve supporting members.

My invention also provides novel means for oscillatably supporting the valve supporting members.

30 The novel features of my invention are hereinafter fully described and claimed.

In the accompanying drawings, which illustrate the preferred embodiment of my invention,

35 Figure 1 is a front elevation of my improved valve grinding mechanism.

Fig. 2 is a top view of the same.

Fig. 3 is a rear elevation of the same.

40 Fig. 4 is an enlarged vertical cross section on the line 4—4 of Fig. 3.

Fig. 5 is an end elevation of the valve grinding mechanism.

Fig. 6 is a vertical sectional view on the line 6—6 of Fig. 4.

45 Fig. 7 is a view similar to Fig. 6, showing mounted in the box, a gear wheel of less diameter than that shown in Fig. 6.

Similar reference characters designate similar parts in the different views.

50 1 designates a supporting frame, which is adapted to be mounted upon any suitable support, such as a bench 2.

55 The frame 1 is provided with a longitudinal vertically disposed board 3, on the rear side of which are mounted a plurality of

boxes, each comprising an inner member 4, to the outer side of which is secured an outer cup-shaped member 5, which is secured to the member 4 by means of bolts 6 which extend through the board 3. 60

A plurality of spur-gear wheels 7 are respectively oscillatably mounted in the members 5. Each gear wheel 7 is provided with an elongated hub 8 which is oscillatably mounted in and extends through the box 65 members 4 and 5 and also through a box 9, which is secured to the front side of the board 3, by means of bolts 10.

The hub 8 of each gear wheel is provided with an axial hole, preferably square in 70 cross section and which has fitted in it the squared portion of a horizontal transverse shaft 11, the forward end of which is externally screw-threaded and has fitted thereon a nut comprising an internally 75 screw-threaded sleeve 12 which bears against the adjacent end of the hub 8 and which is adapted to have removably fitted in it the threaded stem 13 of an adapter 14, the outer end of which is provided with 80 a longitudinal axial hole 15, which is adapted to receive and support the stem of a valve, not shown, which is to be ground. The adapter 14 is provided with a set screw 16, which is adapted to bear against and hold 85 the stem of the valve in the adapter.

Each shaft 11 is provided with a shoulder 17, Fig. 4, which bears against the rear end of the hub 8.

The rear end of the shaft 11 is provided 90 with a longitudinal axial screw-threaded hole 18, which is adapted to receive the screw-threaded stem 13 of another adapter 14, which corresponds in construction to the adapter already described. 95

Meshing with the gear wheels 7 is a longitudinal horizontal reciprocative rack 19, which is provided with a longitudinal flange 20, Fig. 4, which overlaps and engages the outer sides of the gears 7. 100

Each box member 4 is provided, above the hub 8, with a vertical radial slot 21, in which is mounted a bolt 22, which extends rearwardly parallel with the shaft 11 and which has mounted on it a sleeve 23, which 105 is held clamped at its inner end against the member 4, by means of a nut 24 mounted upon the threaded outer end of the bolt 22.

Rotatably mounted on the sleeve 23 is a roller 25, which is adapted to have rolling 110

engagement with the upper side of the rack 19, and which is provided with a peripheral flange 26, which engages the outer side of the rack 19 for retaining the rack engaged 5 with the gear wheels 7.

The bolt 22, sleeve 23 and nut 24 form a roller support, which is radially adjustable in the slot 21 of the member 4, for the purpose of permitting different size gear wheels 10 being mounted in the box members 5. In Fig. 7, I have shown mounted on the shaft 11 a spur gear wheel of smaller diameter than the gear wheel 7. For engagement with such smaller gear wheels, the rack 19 is lowered, as are the rollers 25 and their supports. By using such smaller gear 15 wheels, the speed of oscillation of the shafts 11 may be increased without changing the speed of the driving shaft which operates 20 the mechanism.

Mounted in the frame 1 and adapted for continuous rotation is a driving shaft 28, which has mounted on it a tight pulley 29 and a loose pulley 30 adapted to be engaged 25 and driven by a belt, not shown, which is adapted to be shifted from one pulley to the other by means of a belt shifter 31, which may be of any suitable construction. In the drawing, I have illustrated the belt shifter 30 lever as being pivotally mounted on a platform 32 with which the frame 1 is provided. The under side of the lever 31 has a milled portion 33, which engages with the similar 35 milled portion of a plate 34 secured to the platform 32. The lever 31 is pivoted to the platform 32 by means of a vertical bolt 35, having on its upper end a nut 36, which bears against the upper end of a coil spring 37, Fig. 5, which bears against the lever 31.

For reciprocating the rack 19, the latter has pivoted to it one end of a link 38, the other end of which is pivoted by a transverse bolt 39 to the upper end of a vertical lever 40, which is pivoted by a transverse 45 horizontal bolt 41 to and between the board 3 and a plate 42 which is secured to the rear side of said board. The lower end of the lever 40 is pivoted by a transverse bolt 43 to one end of a longitudinal connecting rod 44, the other end of which is pivoted to a transverse crank pin 45, Fig. 3, with which a bevel gear 46 is provided. The gear wheel 46 is mounted upon a horizontal transverse stud 47, which is secured to the frame 1. Meshing with the gear wheel 46 is a bevel gear wheel 48, which is rigidly secured to the driving shaft 28. The latter shaft is disposed parallel with the rack 19. The above described arrangement of the shaft 28 50 and the transmission which connects it with the rack 19 affords a compact construction, which enables four operators to simultaneously use the grinding mechanism, two of the operators being stationed at the forward 55 side of the frame and two at the rear side 60 65 70 75 80 85 90 95 100 105 110 115 120 125 130

thereof. Each operator may with the use of both hands, grind two valves, which are respectively held in two adjacent holders 14.

In the operation of my invention, when the belt shifter lever 31 is shifted to throw the belt onto the tight pulley 29, the driving shaft 28 will be rotated, thus rotating the gear 46 by means of the gear 48, and thereby reciprocating the rack 19 through the intermediary of the rod 44, lever 40 and link 38. The reciprocation of the rack 19 oscillates the gear wheels 7 and with them the shafts 11 and the valves carried thereby.

The box members 4 and 5 provide each a chamber 49, Fig. 4, adapted to contain oil in which the gear will run. The box member 5 may be provided with an oil hole 50, with which the forward portion of the hub 8 may be lubricated. The box 9 may be provided with an oil hole 51 for receiving oil to lubricate the adjacent ends of the hub 8.

I do not limit my invention to the structure shown and described, as modifications, within the scope of the appended claims may be made without departing from the spirit 90 of my invention.

What I claim is:—

1. In a valve grinding mechanism, a supporting frame, a box mounted thereon, a gear wheel in said box having a hub oscillatably mounted in said box, a shaft mounted in and oscillatable with said hub and having means for holding a valve to be ground, a roller support secured to said box, a roller rotatable on said roller support and having a peripheral flange, a reciprocative rack meshing with said gear wheel and having its outer longitudinal side engaging and guided by said flange and having its upper side adapted to engage the periphery of said 105 roller and having on its under side a longitudinal flange engaging the outer side of said gear wheel, and means for reciprocating said rack.

2. In a valve grinding mechanism, a supporting frame, a box secured thereto, a gear wheel having a hub oscillatably mounted in said box, a shaft mounted in and oscillatable with said hub and having means for holding the valve to the ground, a roller support adjustable toward and from said gear wheel on said box, a roller rotatable on said roller support, a rack meshing with said gear wheel and having rolling engagement with said roller, and means for reciprocating in 120 said rack.

3. In a valve grinding mechanism, a supporting frame, a box mounted thereon, a gear wheel having a hub oscillatably mounted in said box, a shaft extending through and rotatable with said hub and bearing against one end of said hub and having a screw-threaded end, a nut mounted on said screw-threaded end and bearing against the other end of said hub, the opposite end 130

of said shaft having means for supporting a valve to be ground, a rack meshing with said gear wheel, and means for reciprocating said rack.

5 4. In a valve grinding mechanism, a supporting frame, a box secured thereto, a gear wheel having a hub oscillatably mounted in said box, a shaft extending through and oscillatable with said hub and bearing

10 against one end of said hub and having one end externally screw-threaded, a screw-threaded sleeve fitted on said screw-threaded end and adapted to receive an adapter for supporting a valve to be ground, the other

15 end of said shaft having means for supporting an adapter adapted to support another valve to be ground, a rack meshing with said gear wheel, and means for reciprocating said rack.

20 5. In a valve grinding mechanism, a supporting frame, a box secured thereto, a gear wheel having a hub oscillatably mounted in said box, a shaft mounted in and oscillatable with said hub, means carried at opposite 25 ends of said shaft for respectively supporting two valves to be ground, a reciprocative rack meshing with said gear wheel, and means for reciprocating said rack.

6. In a valve grinding mechanism, a supporting frame, a box secured thereto, a gear wheel rotatable in said box, a shaft secured to and oscillatable with said gear wheel and having means for supporting a valve to be ground, a roller support adjustable toward 35 and from said gear wheel, a rack meshing with said gear wheel and having a longitudinal flange engaging the outer side of said gear wheel, a roller on said roller support adapted to have rolling engagement with 40 said rack and having a peripheral flange engaging the outer side of said rack, and means for reciprocating said rack.

7. In a valve grinding mechanism, a supporting frame, a box secured thereto having a radical slot, a gear wheel having a hub oscillatably mounted in said box, a shaft mounted in and oscillatable with said hub and having means for supporting a valve to be ground, a roller support adjustable in 45 said slot toward and from said gear wheel, a rack meshing with said gear wheel, a roller

mounted on said roller support and adapted for rolling engagement with said rack, and means for reciprocating said rack.

8. In a valve grinding mechanism, a supporting frame, a box secured thereto having a radical slot, a gear wheel rotatable in said box and having a hub, a shaft mounted in and oscillatable with said hub, a rack meshing with said gear wheel, the shaft having 55 means for supporting a valve to be ground, a roller support adjustable in said slot toward and from said gear wheel, a roller mounted on said roller support and adapted to have rolling engagement with said rack 60 and having a peripheral flange engaging the outer side of said rack, and means for reciprocating said rack.

9. In a valve grinding mechanism, a supporting frame, a box secured thereto, a gear 70 wheel rotatable in said box, a shaft extending through and oscillatable with said gear wheel and having at one end a screw-threaded hole and having its other end externally screw-threaded, a screw-threaded 75 sleeve fitted on the externally threaded end of said shaft, two adapters respectively fitted in said sleeve and said screw-threaded hole and adapted to respectively support two valves to be ground, a rack meshing with 80 said gear wheel, and means for reciprocating said rack.

10. In a valve grinding mechanism, a supporting frame, a box secured thereto, a gear wheel having a hub oscillatably mounted in 85 said box, a shaft extending through and oscillatable with said hub and bearing against one end of said hub and having one end externally screw-threaded and a screw-threaded hole in its other end, a screw- 90 threaded sleeve fitted on the externally threaded end of said shaft and bearing against the other end of said hub, two adapters fitted respectively in said sleeve and in said hole and adapted each to support a valve to be ground, a rack meshing with 95 said gear wheel, and means for reciprocating said rack.

In testimony whereof I have signed my name to this specification.

HOMER S. DOUGLASS.
